FUSED, POLARIZED, MALE TO FEMALE
BLADE-TYPE ADAPTERClarence R. Curtis, Lombard, Ill., assignor to F. H.
Smith Manufacturing Company, Chicago, Ill.,
a corporation of Illinois

Application August 9, 1950, Serial No. 178,532

17 Claims. (Cl. 200—115.5)

1

This invention relates to a fused, polarized, male to twin female blade-type adapter. This adapter is one of the fused, polarized, blade-type electrical couplings invented by applicant in the course of the general development described in the copending application Serial No. 159,037 filed April 29, 1950. In this copending application, there is shown an adapter connecting a pair of blades to a single receptacle. The features of that adapter are a fuse cartridge chamber in the hot line having an opening thereto through the blade surface of the housing with a fixed electrode and an elastic electrode. The wall leading to the elastic electrode is sloped to act as a guide and there is an ejector window adjacent the chamber. All of these features are in the adapter which is the subject of this application, but there are differences due to connecting two blades to two receptacles instead of to one receptacle.

The general object of this invention is to provide a blade-type twin receptacle adapter having all of the features of the single receptacle adapter shown in the copending application, in as compact a form as possible. One of the features of the invention is the mounting of the elastic electrode on a conductor carrying a pair of female contacts each associated with one slot of one receptacle. A single fuse is used for both outgoing lines and to this extent, a slightly heavier fuse should be used.

One specific object of this invention is to utilize a single connector between the fuse chamber and the two hot female contacts in each socket. In order to do this, proper tensioning must be provided at three points, and this tensioning must not interfere with ready assembling in the housing. As will be seen in the description that follows, applicant herein discloses two embodiments, one wherein the hot line slots of the two receptacles are positioned adjacent each other, and the other wherein the two ground line slots are placed adjacent to each other. In either case, a single connector for the hot line between the fuse chamber and the receptacles is used.

Another object is to maintain as low as possible the number of electrical connectors necessary for the adapter in order to simplify the problem of assembly.

Another object is to provide a method of quickly assembling applicant's adapters.

These and other objects as may hereinafter appear are attained in the two embodiments of the invention shown in the accompanying drawings.

Figs. 1 through 7 relate to the first embodiment of applicant's invention and in these:

Fig. 1 is an exploded perspective view of the first embodiment of applicant's twin receptacle blade-type adapter;

Fig. 2 is a perspective view showing the adapter assembled with a cartridge fuse partially inserted;

Fig. 3 is a view in section taken on the line 3—3 of Fig. 2;

10 Fig. 4 is a view taken on the line 4—4 of Fig. 3;

Fig. 5 is a view taken on the line 5—5 of Fig. 3;

Fig. 6 is a sectional view of the adapter taken on the line 6—6 of Fig. 2; and,

15 Fig. 7 is a front view of the receptacle surface of the adapter showing the slots.

Figs. 8 through 12 relate to the second and preferred embodiment of applicant's invention, wherein:

20 Fig. 8 is an exploded, perspective view of applicant's preferred twin receptacle polarized, blade-type adapter positioned vertically above its assembly jig to indicate the order of assembly;

Fig. 9 is a perspective view of this adapter assembled with a cartridge fuse partially inserted 25 through its ejector window;

Fig. 10 is a face view of the inside of the adapter's base;

Fig. 11 is a sectional view taken on the line 11—11 of Fig. 9; and,

30 Fig. 12 is a side elevation of the window and chamber side of the adapter, partially cut away, to show the relationship of the electrodes or terminals in the cartridge fuse chamber and the manner of sliding a cartridge fuse into position.

35 Continuing to refer to the drawings, the adapter consists of a pair of complementary, similarly sized housings which for descriptive purposes may be referred to as a base 10 and a cap 12. The base has five through openings, namely, referring to Fig. 7, a pair of ground slots 14 and 16, a pair of hot line slots 18 and 20, and a hole 22 through which passes an assembly screw 24.

40 Returning to Fig. 1, the base 10 carries the hot line contacts and comprises a cartridge fuse chamber 26, and an ejector window 28. A rigid hot line blade 30 is formed integrally with the fixed position electrode 32 and the clearances of the walls are such that it seats as shown in Fig. 1 so snugly that it will not drop out of the base 10.

45 Continuing to refer to the base 10 in Fig. 1, there are various cut-out portions for the purpose of reducing the quantity of plastic required, but there is a horizontal passageway through the points 34 to receive the base portion 36 of a connector generally identified by the numeral

50 55

38. The flat electrodes 40 and 42 constitute the female contacts that seat behind the slots 20 and 18 respectively. Their exact position with respect to the slots 20 and 18 may be seen better by referring to Fig. 4. As there shown, the electrodes 40 and 42 each have guide portions 44 and 46 to assure proper direction of an incoming blade against the electrodes 40 and 42. The thickness of the connectors 38 and 48 is $\frac{1}{2}$ inch. They are heavy and elastic and the deflection of either 40 or 42 by a blade will hold the blade in the connector as tightly as required by Underwriters' Laboratories, Inc. specifications.

The numeral 48 identifies the elastic electrode for holding the fuse. When a fuse 50 is in position as shown in Fig. 4, the elastic electrode occupies the position there shown. When a fuse is not in position, it abuts the shoulder 52 as indicated by the dotted line 54. The electrode 48, therefore, is movable toward and away from, but diagonally, the far side of the opening 70 in the cap 12, hereinafter described. The electrodes 40 and 42 and the lower portion of the electrode 48 which is fastened to 36, so as to be spaced from electrode 42, project well above the surface of the base 10 and seat themselves in the chambers 56 and 58 of the cap 12, see Fig. 5.

The cap 12 on its outer face carries an opening 60 through which the ground blade 62 will project, and an opening 64 through which the hot line blade 30 will project. There is also a threaded hole 66 into which seats the bolt 24 for holding the cap and the base in assembled relationship. Also through the face 68 of the cap 12 is the chamber opening 70. The wall 72 of this chamber opening is slightly sloped with respect to the face 68 and terminates in the same plane as the fuse-engaging surface of the electrode 32. This relationship is suggested in Fig. 6. Interiorally of the cap 12 is a guide ramp 74, referring to Fig. 6, and as one pushes a fuse cartridge such as 50 through the opening 70, the ramp 74 will guide it against the elastic electrode 48. By pressing it further into the opening, it will move the elastic electrode 48 to the right and the electrode 76 will slide along the wall 72 and then slip onto the surface of the fixed electrode 32.

On the other hand, when a knife or screw driver is inserted through the ejector window 28, which has a slight extension 78 in the cap, the cartridge will move toward the opening and when the electrode 76 is clear of the wall 72, the spring electrode 48 will eject it. Perhaps the best way to describe the ejector action is to state that when the inside edge of the electrode 76 reaches the point where the lead line 72 engages the wall, the cartridge fuse will snap the rest of the way and will be thrown free and clear for a substantial distance. The foregoing description completes the hot line assembly.

The ground line is somewhat simpler. This connector bears the numeral 80, see Fig. 1, and has a general U-shape with the ground blade 62 mounted near its central portion. Each arm constitutes a female contact 82 and 84, which respectively seat in chambers 88 and 86, in the cap 12. Each electrode has a guide finger, namely, 90 and 92, which respectively seat in the chambers 87 and 89 into which open the ground line slots 16 and 14 respectively. Referring to Fig. 5, the connector 80 is set so as to snugly engage the confining walls of the passageway in which it seats.

Referring to Fig. 1 the cartridge consists of

two electrodes 76 and 94 spaced by an insulating tube 96 containing the fuse wire, which tube is made of a ceramic or glass or other non-conductive plastic.

5 Examining now the preferred form of the invention, and referring to Figs. 8 through 12, the numeral 100 generally identifies a twin receptacle polarized adapter consisting of a base 102, a cap 104, and ejector window 106, a portion of which 108, is through a wall of the base 102 and the balance of which is through a wall of the cap 104.

15 Referring to Figs. 8 and 10, the base 102 has a pair of guide lugs 112 and 114 to facilitate assembly with the cap 104. The hot line slots are indicated by the numerals 116 and 118 and the ground line slots by the numerals 120 and 122. This arrangement should be compared to that 20 shown in Fig. 7 of the first embodiment where the ground slots are on the outside and the hot slots are on the inside. There is a hole 124 centrally of the slot face 126 of the base 102 through which may be passed a threaded bolt 128 which 25 may be screwed into an opening 130 in the cap 104. Located in the base adjacent the wall containing the ejector window 106 is the fuse chamber 132.

30 The cap 104 has a passageway or fuse opening 134 which aligns itself with the fuse chamber 132 when the cap and the base are assembled together, see Figs. 11 and 12. The outside face of the cap 104 may be called the blade face 136 and the walls of the opening 134, namely, 138, 140, are sloped with respect to the face 136 so as to facilitate mounting of the cartridge 142 in the fuse chamber 132. This is best shown in Fig. 12.

35 Both base and cap have interior chambers and passageways designed to accommodate the electrical connectors which carry the hot and the ground lines through the adapter insulated from each other, as the base and the cap of both embodiments are made of electrical insulating material.

40 The hot line through the adapter consists of two connectors, 144 and 162. The connector 144 has a broad U-shaped configuration, see Fig. 10, and comprises an outside band 146, Fig. 8, having an electrode 148 with sloped blade guide 150 on one end and electrode 152 with sloped blade guide 154 at the other end. These electrodes or 45 contacts 148 and 152 are the hot line female contact members of the twin receptacle adapter and are positioned immediately behind the hot line slots 116 and 118. Mounted on a shoulder 50 of the central portion of the connector 144 by a rivet 156 is an arm 158 having an electrode or contact 160 for holding one end of the cartridge fuse 142. This spring electrode 160 flexes over a comparatively long arm of conductive spring material, commencing at the rivet 156, see Fig. 10. This electrode is responsible for 55 positively ejecting a burned out cartridge fuse from the chamber and it is important that its elasticity remain unimpaired by being held in a fixed position over many months of time. It 60 is this long length of the arm 158, which is bent only slightly at any point of its length, that is responsible for the spring electrode 160 resisting the taking of a set while it is being held in a 65 flexed position for a long period of time. This 70 connector 146 is very similar to 36 in Fig. 1.

75 The blade 162 of the hot line is very similar to the blade 30 used in the first embodiment and is inelastic, with the electrode 163 seated at the other end of the fuse chamber, see Fig. 12. The

blade 162 passes through the opening 164, see Fig. 8, in the cap 104.

As in the first embodiment of the invention, the ground line is formed of a single connector generally identified by the numeral 166. Compare with connector 80 in Fig. 1. This connector 166 carries a blade 168 riveted at 170 to a U-shaped connector 172 having an electrode 174 with blade guide 176 at one end thereof and electrode 178 with blade guide 180 at the other end. The blade 168 passes through the opening 182 in the cap 104. The electrodes 174 and 178 respectively constitute the ground line female contacts and are located immediately behind ground slots 120 and 122.

The manner of assembling this adapter is graphically illustrated by Fig. 8. A jig 184 consists of a block 186 carrying four placement lugs 188, 190, 192 and 194, which will exactly position the cap 104 over the opening 196 into which the blades 162 and 168 may be dropped. When the cap 104 is in position, the blade 162 is pushed downwardly, the fit in the hole 164 being quite snug, until the electrode 163 engages the inside face of the cap 104. The blade 168 is then pressed into the opening 182 until the connector 172 engages the inside face of the cap 104. The hot line connector 144 is then seated in the U-shaped recess 198 of the cap 104 with the arm 158 and electrode 160 above the inside face of the cap 104. At this point, the electrodes 148, 152, 174 and 178 are all lying in a generally horizontal plane below the inside face of the cap 104 while the electrode 160 is lying above said face. Thereupon the base 102 is brought down over all of the elements and the bolt 128 is drawn tight. The relationship of the various electrodes in the base can best be seen in Fig. 10.

In comparing the two embodiments of the invention, it will be observed that in each case the ground line is formed by a single conductor, although structurally it is formed of two pieces. That is to say, the blade is rigidly attached to a member carrying both female contacts. It will also be observed that the hot line contact in the fuse chamber is rigidly fastened to a member that carries both of the female hot line contacts.

The mounting of the incoming hot line electrode in the fuse chamber on the blade itself and the mounting of both ground female contacts on the incoming ground blade greatly simplifies assembling and the cost of the parts.

These features could be carried into adapters having more than two receptacles or two receptacles, but on different faces. Some multiple receptacle adapters have a cube configuration with receptacles on several of the faces. This general thought of carrying out the mounting of the hot line fuse chamber contact on the hot line blade and both of the ground female contacts on the female blade could be carried out on such multiple receptacle adapters.

Having thus described his invention, what applicant claims is:

1. An adapter comprising a housing, a ground blade and a hot blade physically different from the ground blade extending from one surface thereof, said blades being electrically conductive, a plurality of blade-type receptacles, a pair of electrically conductive female contacts in each receptacle, a non-fusible conductor connecting the ground blade to one female contact in each receptacle, a chamber for a removable fuse, and a pair of spaced electrodes in said chamber, one electrode connected to the hot

blade and the second electrode connected to the other female contact of each receptacle.

2. An adapter comprising a housing, a ground blade and a hot blade physically different from the ground blade extending from one surface thereof, said blades being electrically conductive, a plurality of blade-type receptacles each having a ground slot for seating a ground blade and a hot line slot for seating a hot blade, an electrically conductive female contact behind each slot, a non-fusible conductor connecting the ground blade to the ground female contact in each receptacle, a chamber for a removable fuse, and a pair of spaced electrodes in said chamber, one electrode connected to the hot blade and the second electrode connected to the hot line female contact of each receptacle.

3. An adapter comprising a housing, a ground blade and a hot blade physically different from the ground blade extending from one surface thereof, a plurality of blade-type receptacles, a pair of female contacts in each receptacle, a non-fusible conductor connecting the ground blade to one female contact in each receptacle, a chamber for a removable fuse, a passageway through the blade surface into the chamber, and a pair of spaced electrodes in said chamber, one electrode connected to the hot blade and the second electrode connected to the other female contact of each receptacle.

4. An adapter comprising a housing, a ground blade and a hot blade physically different from the ground blade extending from one surface thereof, a plurality of blade-type receptacles, a pair of female contacts in each receptacle, a non-fusible conductor connecting the ground blade to one female contact in each receptacle, a chamber for a removable fuse, a passageway through said blade surface into the chamber, an elastic electrode movable toward and away from a portion of said passageway, a conductor connecting said electrode to the hot-line female contact of each receptacle, a second electrode in said chamber and spaced from the first electrode, and a conductor connecting the latter electrode to the hot line blade.

5. The adapter of claim 2 wherein the slots of two of the receptacles are in a single plane surface and in alignment and both hot line slots are between the ground slots.

6. An adapter comprising a housing, a ground blade and a hot blade physically different from the ground blade extending from one surface thereof, a plurality of blade-type receptacles, a pair of female contacts in each receptacle, a non-fusible conductor connecting the ground blade to one female contact in each receptacle, a chamber for a removable fuse, a passageway through said blade surface into the chamber, an elastic electrode movable toward and away from a portion of said passageway, a conductor connecting said electrode to the hot-line female contact of each receptacle, a guide wall extending from the passageway to a point adjacent the elastic electrode, a second electrode in said chamber and spaced from the first electrode, and a conductor connecting the latter electrode to the hot line blade.

7. An adapter comprising a housing, a ground blade and a hot blade physically different from the ground blade extending from one surface thereof, a plurality of blade-type receptacles, a pair of female contacts in each receptacle, a non-fusible conductor connecting the ground blade to one female contact in each receptacle, a chamber for a removable fuse, a passageway through the

blade surface into the chamber, a pair of spaced electrodes in said chamber, one electrode connected to the hot blade and the second electrode connected to the other female contact of each receptacle, and an ejector window into the chamber at a point spaced from both electrodes.

8. An adapter comprising a housing, a ground blade and a hot blade physically different from the ground blade extending from one surface thereof, a plurality of blade-type receptacles, a 10 pair of female contacts in each receptacle, a non-fusible conductor connecting the ground blade to one female contact in each receptacle, a chamber for a removable fuse, a passageway through the blade surface into the chamber, a pair of spaced electrodes in said chamber, one electrode connected to the hot blade and the second electrode connected to the other female contact of each receptacle, and an ejector window through a housing wall normal to the blade face into the 20 chamber at a point spaced from both electrodes.

9. An adapter comprising a housing, a ground blade and a hot blade physically different from the ground blade extending from one surface thereof, a plurality of blade-type receptacles, a pair of female contacts in each receptacle, a non-fusible conductor connecting the ground blade to one female contact in each receptacle, an elongated chamber positioned parallel to a line connecting the two blades and at one side thereof, a passageway through a long wall of the chamber and through the blade face into the chamber, and a pair of spaced electrodes in said chamber, one electrode connected to the hot blade and the second electrode connected to the other female 35 contact of each receptacle.

10. An adapter comprising an insulated housing formed of a base having receptacle slots in one external wall and a cap having blade passageways in one external wall, an open-sided fuse chamber located in the base with spaced electrodes for conductively joining a hot line blade protruding through a blade passageway in the cap to a pair of hot line female contacts also in the base, a pair of female ground contacts conductively connected to a ground blade disposed in the cap, and a passageway through said cap alignable with the open side of the fuse chamber in the base.

11. An adapter formed of an insulated base and an insulated cap, said base comprising a lozenge-shaped body, an elongated open-sided chamber for a cartridge fuse lying parallel and adjacent one of the straight sides, a fixed contact position at one end of said chamber and integrally formed with a blade extending outwardly from the surface of said base, a pair of hot line slots through said base, a U-shaped member having electrical contact arms resiliently aligned with said slots and an extension arm attached thereto and flexibly positioned in the other end of the fuse chamber, and a pair of ground slots through said housing each spaced from a hot line slot to form a receptacle, and said cap comprising a U-shaped recess, a flexible U-shaped member in said recess with its ends carrying contacts seatable in the ground line slots of the base, a ground line blade attached to said U-shaped member and extending from one face of the cap, a passageway through said cap through which may be passed the hot line blade in the base, a through passageway in the cap alignable with the open side of the fuse chamber in the base, and means for holding the base and the cap in assembled relationship.

5 12. The adapter of claim 2 wherein the slots of two of the receptacles are in a single plane surface and in alignment and both ground line slots are between the hot slots.

13. A twin blade to twin slot receptacle adapter comprising a housing, two pairs of blade slots disposed therein, a blade carrying a pair of female contacts positioned behind one slot of each pair of blade slots, a fuse chamber in the housing, a second blade carrying an electrode mounted with the electrode in the fuse chamber, and a connector carrying an electrode mounted in the fuse chamber and also carrying a pair of female contacts, each positioned behind the other slot of each receptacle.

14. A twin blade to twin slot receptacle adapter comprising a housing, two pairs of blade slots disposed therein, the slots of each pair being distinctive and associable respectively with complementary ground and hot blades, a ground blade carrying a pair of female contacts each formed integrally therewith and each positioned behind the ground slot of each pair, a fuse chamber in the housing, a hot blade physically different from the ground blade carrying an electrode which electrode is mounted in the fuse chamber, and a second blade carrying an electrode mounted in the fuse chamber and also carrying a pair of female contacts, each positioned behind the hot slot of each receptacle.

15. A twin blade to twin slot receptacle adapter comprising a housing, two pairs of blade slots disposed therein, the slots in each pair being distinctive from each other and adapted to receive respectively correspondingly distinctive ground and hot blades, a ground blade carrying a pair of female contacts each positioned behind a ground slot, a fuse chamber in the housing, a hot blade carrying an electrode which electrode is mounted in the fuse chamber, said ground and hot blades projecting in parallel from a blade face of the housing, a second blade carrying an electrode which electrode is mounted in the fuse chamber and also carrying a pair of female contacts, each contact being positioned behind a hot slot of each receptacle, and a passageway into the fuse chamber through the blade face.

16. A twin blade to twin slot receptacle adapter comprising a housing, two pairs of blade slots disposed therein, the slots in each pair being distinctive from each other and adapted to receive respectively correspondingly distinctive ground and hot blades, a ground blade carrying a pair of female contacts each positioned behind a ground slot, a fuse chamber in the housing, a hot blade carrying an electrode which electrode is mounted in the fuse chamber, said ground and hot blades projecting in parallel from a blade face of the housing, a second blade carrying an electrode which electrode is mounted in the fuse chamber and also carrying a pair of female contacts, each contact being positioned behind a hot slot of each receptacle, said fuse chamber being elongated and lying parallel to the blade face, and a passageway through the blade face into the chamber.

17. A twin blade to twin slot receptacle adapter comprising a housing, two pairs of blade slots disposed therein, the slots in each pair being distinctive from each other and adapted to receive respectively correspondingly distinctive ground and hot blades, a ground blade carrying a pair of female contacts each positioned behind a ground slot, a fuse chamber in the hous-

ing, a hot blade carrying an electrode which electrode is mounted in the fuse chamber, said ground and hot blades projecting in parallel from a blade face of the housing, a second blade carrying an electrode which electrode is mounted in the fuse chamber and also carrying a pair of female contacts, each contact being positioned behind a hot slot of each receptacle, a passageway into the fuse chamber through the blade face, and a second passageway through another 10 wall of the chamber at a point between the two

electrodes whereby access from outside the housing may be had to the glass portion of a cartridge fuse.

CLARENCE R. CURTIS.
